UNITED STATES PATENT OFFICE

2,663,029

HEAD SUPPORT

Henry B. Whitley and Eunice G. Whitley,
Durham, N. C.

Application December 13, 1951, Serial No. 261,476

3 Claims. (Cl. 5—71)

1

This invention relates to new and useful improvements in head supports and the primary object of the present invention is to provide a small and compact head rest and back support for bed patients that may be quickly and readily adjusted to a comfortable angle.

Another important object of the present invention is to provide a head support composed of parts that are quickly and readily assembled or disassembled to permit the device to be transported as a small article, and which also facilitates cleaning of the flexible backing forming part of the support.

A further object of the present invention is to provide a head support composed of two U-shaped tubular frames that are connected together by a novel and improved means which functions as a combined reinforcing and strengthening member, a pivot and a backing holder.

A still further aim of the present invention is to provide a head support of the aforementioned character that is simple and practical in construction, strong and reliable in use, neat and attractive in appearance, light in weight, inexpensive to manufacture, and otherwise well adapted for the purpose for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention assembled for use;

Figure 2 is a vertical sectional view taken substantially on the plane of section line 2—2 of Figure 1 and showing a user, in dotted lines positioned relative thereto;

Figure 3 is a perspective view of the invention in a folded and used position;

Figure 4 is a vertical sectional view taken substantially on the plane of section line 4—4 of Figure 3;

Figure 5 is a vertical sectional view taken substantially on the plane of section line 5—5 of Figure 1; and,

Figure 6 is a perspective view showing one part of the frame removed from the other main part to illustrate how the backing may be removed for cleaning.

Referring now to the drawings in detail, where-in for the purpose of illustration, there is disclosed a preferred embodiment of the present invention, the numeral 10 represents a U-shaped tubular base frame including a pair of leg por-

2

tions 12 that are joined at one of their ends by a web portion 14. The ends of the base frame and more particularly the free ends of the leg portions 12 are formed with transverse apertures 16 for a purpose presently to be described.

A tubular U-shaped supporting frame 18 comprises the other main half of the present head support and includes a pair of leg portions 20 joined at one of their ends by a web portion or cross-piece 22. The other ends of the leg portions 20 are provided with transverse apertures 24 that register with the apertures 16.

Means is provided for joining the frames 10 and 18 whereby the frame 18 may be pivoted to a desired vertically inclined position. This means comprises a tubular member or cross-bar 26 having internally threaded sleeves or nuts 28 frictionally fitted in its ends. The sleeves 28 abut the leg portions 20 and their bores register with the apertures 16 and 24. Combined bolts and pivots 30 extend through the apertures 16 and 24, and their threaded ends are receivably engaged in the bores of sleeves 28 to pivotally secure the frames together.

25 The ends of flexible backing 32, preferably canvas, are secured to themselves by stitching or the like to provide transverse end casings or sleeves 34 and 36 that receive the web portion 22 and cross-bar 26, respectively. The backing 32 is removably retained on the supporting frame 18 and extends parallel to and between the leg portions 20. Sleeve 34 is slightly curved to conform to the curvature of cross-piece 22.

35 A flexible strap 38, preferably of canvas, extends transversely between leg portions 20 and its ends are secured to themselves to provide casings or sleeves 40 that slidably receive the leg portions 20. Strap 38 is also removably retained on frame 18 and extends transversely across and behind the backing to reinforce and strengthen the same. Strap 38 also prevents undue sagging or flexing of the backing.

40 Means is provided for retaining the frame 18 vertically inclined relative to the frame 10. This means comprises a U-shaped brace 42 having in-turned lateral projections 44 at its ends that enter apertures 46 provided in the leg portions 20 of frame 18. Pairs of longitudinally spaced L-shaped lugs 48 are suitably fixed to the leg portions 12 of frame 10 and coact with the leg portions 12 in defining channels for selectively receiving the web portion of brace 42.

Member 26 and its associated fasteners 28, 30 functions as a combined reinforcing and strengthening means for base frame 10, a pivot means for

the frame 18, a connection between the two frames and a retainer or holder for the backing. The frames are readily disassembled by removing bolts 30, after which backing 32 and strap 33 may be removed from frame 18, for cleaning, repair or the like.

Having described the invention, what is claimed as new is:

1. A head support comprising a U-shaped tubular base frame, a U-shaped tubular supporting frame, means pivotally and removably securing the ends of the base frame to and against the facing peripheries of the ends of the supporting frame, a brace swingably carried by the supporting frame, means secured to the base frame engaging the brace to retain the supporting frame inclined relative to the base frame, a removable backing having terminal sleeves removably engaging the web of the supporting frame and the first named means, and a supporting strap removably supported solely by the supporting frame and extending behind the backing, said supporting strap having terminal sleeves receiving the limbs of the supporting frame, said first named means includes a tubular cross bar extending between the ends of said base frame, an internally threaded sleeve fitted in each end of said bar and engaging the facing peripheries of the ends of said base frame, and bolts extending through the ends of both frames and threaded in said last named sleeves.

2. A back and head rest comprising first and second U-shaped tubular frames, a tubular cross bar extending between the ends of said first frame, a pair of nuts fitted in the ends of said bar engaging the facing peripheries of the ends of said first frame, each of said frames having transverse apertures in their ends in registry with each other and said nuts, bolts extending through said apertures and threaded in said nuts to pivotally secure the ends of the frames to-

gether, said second frame including a web portion remote from said bar, a removable flexible backing having terminal sleeves receiving said bar and said web portion, and a brace carried by the second frame engaging the first frame to retain the frames inclined relative to each other.

3. A back and head rest comprising first and second U-shaped tubular frames, a tubular cross bar extending between the ends of said first frame, a pair of nuts fitted in the ends of said bar and engaging the facing peripheries of the ends of said first frame, each of said frames having transverse apertures in their ends in registry with each other and said nuts, bolts extending through said apertures and threaded in said nuts to pivotally secure the frames together, said second frame including a web portion remote from said bar, a U-shaped brace swingably carried by the second frame, a plurality of pairs of lugs supported on the first frame for selectively engaging the brace to retain the second frame inclined relative to the first frame, and an elongated flexible backing having transverse end sleeves receiving said bar and said web portion.
